Primary Examiner — Lauren R Calve(74) *Attorney, Agent, or Firm* — Cooley LLP; Michael S. Tuscan; Anna Miron(57) **CLAIM**

The ornamental design for a handle, as shown and described.

DESCRIPTION

FIG. 1 is a side perspective view of a handle;

FIG. 2 is another side perspective view thereof;

FIG. 3 is a front view thereof;

FIG. 4 is a back view thereof;

FIG. 5 is a top view thereof; and,

FIG. 6 is a bottom view thereof.

Broken lines are directed to environment and are for illustrative purposes only; the broken lines form no part of the claimed design. The claim includes the mirror images of FIGS. 1-6.

1 Claim, 6 Drawing Sheets(56)
